CLAIM

The ornamental design for a pet carrier backpack as shown and described.

DESCRIPTION

FIG. 1 is a perspective view of a pet carrier backpack showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a view showing the application thereof with the curtains of a pet carrier backpack in a rolled up position;

FIG. 10 is a view showing the pet carrier backpack in an open configuration of use; and,

FIG. 11 is another view showing the pet carrier backpack in an open configuration of use.

The broken lines in the pet carrier backpack depict stitching that form no part of the claimed design. The dash-dot-dash broken lines in the FIGS. 9-11 depict portions of the pet carrier backpack that form no part of the claimed design. All other broken lines in the figures depict portions of the article and form no part of the claimed design.

1 Claim, 11 Drawing Sheets
